F. H. HIBBARD

JIG FOR ASSEMBLING COORDINATE SWITCHES

Filed July 20, 1923

Inventor:
Frank H. Hibbard
by S. W. Adams Atty.

Patented Sept. 9, 1924.

UNITED STATES PATENT OFFICE.

FRANK H. HIBBARD, OF ARLINGTON, NEW JERSEY, ASSIGNOR TO WESTERN ELECTRIC COMPANY, INCORPORATED, OF NEW YORK, N. Y., A CORPORATION OF NEW YORK.

JIG FOR ASSEMBLING COORDINATE SWITCHES.

Application filed July 20, 1923. Serial No. 652,750.

To all whom it may concern:

Be it known that I, FRANK H. HIBBARD, a citizen of the United States of America, residing at Arlington, in the county of Hudson and State of New Jersey, have invented certain new and useful Improvements in Jigs for Assembling Coordinate Switches, of which the following is a full, clear, concise, and exact description.

This invention relates to a jig for use in assembling telephone switches. More particularly it refers to a jig used in the assembly of the so-called coordinate switch for holding the retracting springs in adjusted position with reference to their associated active wires to facilitate the assembly of their supporting members on the switch frame.

The object of the invention is the provision of means whereby certain operating parts of the switch referred to above may be easily assembled.

A feature of the invention is the provision of means whereby a plurality of resilient supports each serving a set of active contacts are held collectively in tensioned position to facilitate their assembly on the switch structure with which they form a part.

Another feature is the provision of means whereby the retracting spring of each active contact set is held in line parallel with reference to its associated set of active contact wires in order to facilitate the mounting of the camming cards thereon.

Other features and advantages will appear from the following description and the drawings in which Fig. 1 is a right hand side assembly view of an active contact wire supporting member showing the jig and the retracting springs held thereby in tensioned position, Fig. 2 is a sectional view of Fig. 1 taken approximately on line 2-2 and seen in the direction indicated by the arrows, Fig. 3 is a front view of a set of active and passive contacts showing the camming card in assembled position, and Fig. 4 is a portion of the retracting spring supporting plate showing the relative position of the active contact wires with reference to the re-tracting spring.

Similar reference characters refer to similar parts through the several views.

The switch structure in which the present invention is particularly well adapted for use is shown partially in Fig. 1 and gener-

ally consists of a plurality of sets of active contacts molded into an insulating upright support 20, which is securely arranged at both ends on the cross bars 10 and 11 of the switch frame (not shown). Each active contact set generally consists of a plurality of bare wires 21, 22 and 23, the free ends of which extend laterally from support 20, through apertures 24 in a supporting plate 25 in engageable relation with associated grid wires 26, 27 and 28 held in spaced relation with reference to their associated active contact wires by means of insulating strips 29, one of which is shown partially in Fig. 1.

For each set of active contact wires 21, 22 and 23, there is provided a retracting spring 30 secured on the insulating bar 20 and a movable camming card 31. Normally, the retracting spring 30 lies in retracted position as indicated by the dotted line in the upper set of active contact wires shown in Fig. 1. Consequently, in order to easily pass the active contact wires 21, 22 and 23 and their retracting springs 30 through their respective apertures 24 and to put the camming cards 31 in position on the contact wires 21, 22 and 23, when the support 20 is secured on the cross bars 10 and 11, it is necessary to hold the retracting springs 30 of each bar 20 collectively and in line parallel with the normal direction of the active contacts in order that the active contacts and the retracting spring may register with their associated apertures in the camming cards 31.

The jig used for this purpose consists of a metal strip 32 having a plurality of laterally extending arms 33 each provided at its free end with a hook 34 adapted to hold its respectively associated retracting spring 30 in line parallel with reference to the direction of the active contacts to permit the passing of the active contact sets and their retracting springs through the apertures of the supporting plate in order to assemble the upright supports on the switch frame and to permit the assembly of the camming cards on the contact wires.

The strip 32 carries a plurality of locating pins 35 (one of them being shown in Fig. 2) which register with locating holes 39 in eyelets 37. The eyelets 37 are provided to hold the reinforcing strips 38 and the retracting springs 30 in assembled position on the upright support 20. The strip 32 is

held at each end on the upright support 20 by means of clamps each consisting of a movable handle lever 49 pivoted on the stationary handle lever 40 and acted upon by 5 means of a spring 41 tensioned to close the movable handle levers 49 against the reinforcing strip 38. The stop pins 42 are provided to limit the movement of the movable handle lever 49 and to assist in positioning 10 the supports on the jig.

What is claimed is:

1. A jig for assembling a switching device, said jig comprising a bar, a plurality of laterally extending arms thereon, and 15 means on each of said arms for retaining springs in tensioned position during the assembly of the switch.

2. A jig for restraining the contact set tensioning springs in a coordinate switch 20 structure, said jig comprising a strip, a plurality of laterally extending arms disposed at regular intervals thereon and having their free end portions bent to receive said springs and hold them in position.

25 3. A jig for holding the active contact retracting springs in a switching device, comprising a strip, a locating pin arranged on each end of said strip registering in holes in the supporting member for said contacts 30 and springs, and means for holding said strip in adjusted position on said member to facilitate the assembly of said springs in said device.

35 4. A jig for use in the manufacture of telephone switches, said switches having a frame, upright supports, contact sets arranged on said supports, a retracting spring for each of said sets, a camming card for loosely connecting one of said springs to

each of said contact sets, said jig comprising 40 a bar, a plurality of laterally extending arms integrally formed therewith, and a hook on each of said arms for holding the retracting springs in position for assembling said supports on said frame and said 45 cards on said contacts.

5. A jig for assembling switches having supports, sets of active contact wires and retracting springs on each of said supports, an apertured plate through which said contact sets protrude, and a tie member for each of said sets, said jig comprising a bar, a plurality of locating pins arranged thereon for locating said bar on said supports, a plurality of laterally extending 55 arms on said bar for holding the retracting springs in spaced relation with the active contacts for assembling the tie members and a pair of clamps for retaining said support on said jig while positioning said support 60 on said switch.

6. A jig for assembling telephone switches having sets of active contacts and retracting springs arranged on insulating supports, a frame for said supports, a tie member associated with each of said contact sets, a jig for holding said retracting springs tensioned to permit the assembly of said tie members on said contact sets, pins on said 65 jig registering with similarly disposed holes in said support for locating said support on said jig and means for holding said support on said jig for assembling said support on said frame.

In witness whereof, I hereunto subscribe 75 my name this 13 day of July A. D., 1923.

FRANK H. HIBBARD.
